UNITED STATES PATENT OFFICE.

GEORGE HOLDEN, OF MERCHANTVILLE, NEW JERSEY, ASSIGNOR TO
MERRITT AND COMPANY, A CORPORATION OF NEW JERSEY.

WINDOW-SCREEN.

No. 822,948.

Specification of Letters Patent.

Patented June 12, 1906.

Application filed September 14, 1905. Serial No. 278,408.

To all whom it may concern:

Be it known that I, GEORGE HOLDEN, of Merchantville, county of Camden, and State of New Jersey, have invented an Improvement in Window-Screens, of which the following is a specification.

My invention has reference to window-screens; and it consists of certain improvements which are fully set forth in the following specification and shown in the accompanying drawings, which form a part thereof.

Heretofore window-screens have been made with a spring-roller attached to the lower bar of the lower sash-frame and from which the screen of cloth has depended and attached at its lower edge to the window-sill, so that as the window-sash is raised the screen is unwound from the roller, just filling the space exposed by the raising of the sash, and, conversely, when the window-sash is lowered the screen automatically winds up upon the roller. This construction, while having general utility, had several defective and unsatisfactory features, among which may be mentioned that the attachment of the screen directly to the window-sill was objectionable, in that it was necessary to remove the screws to permit the screen to be detached when it was not desired to have the screen in the window, and aside from the inconvenience of such attachment the screw-holes in the window-sill were apt to permit rotting thereof by penetration of water when the screen was not in place. Furthermore, where the window-sill was not level or where the roller was not attached to the window-sash absolutely accurately at right angles to the travel of the sash the screen would not adjust itself so as to be taut at each side or selavage and would thereby vibrate and allow the insects to pass into the room. Further, the edges of the screen were not held against the action of drafts when the window-sash was fully raised, and consequently the desired security against the passage of insects was very ineffectual.

The object of my invention is to provide a construction of window-screen of the general nature of that above referred to, but which shall obviate the defects mentioned and which shall, furthermore, embody in its construction many details adapted for the more practical and convenient use of a screen of this nature.

My invention consists of a spring-roller attachment adapted to be secured to the window-sash and from which a suitable screen depends, the lower edge of which is combined with an end bar pivoted to a base-bar adapted to be held in position adjacent to the window-sill, whereby the screen may adjust itself automatically with respect to its attachment to the window-sill.

My invention further consists in combining the above features with socket portions secured to the side of the window-frame and with which the base-bar detachably interlocks and by which it is held in position close to the window-sill without any direct connection with said window-sill.

My invention further embodies in a window-screen of the general character described a construction in which there are vertical side bars against which the lateral or selvage edges of the screen rest and to which they are clamped at suitable places to hold them in place when the window-sash is raised to a considerable extent.

My invention also embodies in the construction last mentioned suitable cam devices on the window-sash or the frame carrying the spring-roller for operating the clamps on the side bars, so that when the window-sash is raised or lowered the clamps will be automatically opened at the proper time to release the window-screen or closed to permit it to be clamped, as will be more fully understood from the description to follow.

My invention also embodies details of construction which, together with the features above mentioned, will be better understood by reference to the drawings, in which—

Figure 1 is a cross-section through a window frame and sash with my improvements applied thereto, and taken on line $x-x$ of Fig. 2. Fig. 2 is an elevation of the same with the window-sash slightly raised. Fig. 3 is a vertical section of the same on line $y-y$ of Fig. 2. Fig. 4 is a vertical section through the spring-roller and its supporting-frame, taken on line $t-t$ of Fig. 6. Fig. 5 is a perspective view of one end of the spring-roller-supporting frame. Fig. 6 is a transverse section through Fig. 4 on line $z-z$. Fig. 7 is a perspective view showing the bars for the lower end of the screen and the lower part of one of the side bars. Fig. 8 is a perspective view of a portion of the side bars, showing the clamp.

Fig. 9 is a vertical section through the screen and its attachments when removed from the spring-roller; and Fig. 10 is an enlarged sectional view of the spring-roller, showing the 5 method of attaching the screen thereto.

A is a window-frame and may be of any ordinary construction with the parting beads or strips A' separating and guiding the sashes.

B is the lower sash.

- 10 C is a spring-roller case, in which the spring-roller D is secured, and said case is attached to the outside of the lower bar of the sash B by screws passing through the lug C³. These lugs have elongated holes c, so as to 75 permit a slight adjustment of the frame C, whereby buckling or uneven tension on the screen may be obviated, as aforesaid. The case C comprises two parts C' and C², telescoping into each other and leaving an open 15 throat C⁵, through which the screen may pass. The parts C' and C² are closed at their outer ends by end plates C⁴, which are provided with cams H and also the aforesaid lugs C³, as clearly shown in Fig. 5. The 20 spring-roller is clearly shown in Figs. 4, 6, and 10. It consists of a wooden part D', to one end of which is secured a metallic sleeve D², having a pivot d, journaled in one of the end frames D⁴. The other end of the wooden 25 part D' is fitted with a second metallic sleeve D³, inclosing the spring G' and the spindle G, which is provided with the usual rectangular end fitting a corresponding hole in the other end plate C⁴ of the frame C. One end of the 30 spring G' is secured to the spindle G and the other end is secured to the wooden part D'. By this construction it is evident that the 35 length of the roller may be increased or decreased to suit the length of the frame C, 40 which is made to correspond to the particular width of the window-sash. This adjustability of the parts D and C is a great convenience in the manufacture, as it permits these parts to be adapted to any particular width 45 of window without material expense and without having to keep an unreasonable stock of the goods of various lengths on the hands of the manufacturer. The sleeves D² and D³ are formed with longitudinal grooves 50 D⁴, which have an over hanging shoulder D⁵. The sleeves are formed, preferably, by bending a sheet of metal into a cylinder with the particular method of joining the ends shown in Fig. 10, which forms the groove and overhanging shoulder.

- The wooden part D' of the roller is simply formed with a groove D⁶, into which the grooved portions of the sleeves extend, as will be clearly understood from the drawings. 60 The screen E may be made of any suitable material, but preferably of suitably-sized mesh mosquito-netting. The upper end is secured to a transverse flat rod L, which is inserted in the groove D⁴ of the roller, the edges 65 of the rod next to the screen being inserted

under the overhanging shoulder, as indicated in Fig. 10, so that any pull upon the screen cannot pull the rod out of the groove. This is a simple and inexpensive method of securing the screen to the roller and, moreover, 70 does not interfere with the rod being removed when necessary.

The lower end of the screen E is clamped to a transverse frame F, which comprises an end bar F' and a bottom bar F², secured together by a single pivot f. The bottom bar is preferably U-shaped, and between the upwardly-extending parts thereof the lower edge of the end bar F' extends, as clearly shown in Figs. 7 and 9. In this manner the 75 bar F' may be oscillated on the bar F², so as to automatically adjust itself.

The bottom bar F² is provided at each end with laterally-extending lugs F³. These lugs are inserted in sockets I' on the lower 80 ends of the side bars I, which side bars are secured to the parting-beads immediately outside of the window-sash, as is clearly shown in Figs. 1 and 2. In this manner the bottom bar is readily secured in place and 85 close to the window-sill without any direct attachment to the window-sash itself. Moreover, the connection between the flanges F³ and the sockets I' is such that the said bottom bar may be coupled and uncoupled with 90 said sockets readily, so that when the screen is not desired to be used the bottom bar may be uncoupled and permitted to rise and fall with the window-sash and remain close up to the frame C containing the spring-roller, 95 it being held in that position by the winding action of the roller exerted through the screen.

The side bars I are L-shaped and are 100 screwed to the parting-beads through suitable parts of the window-frame and the lateral edges or selvages of the screen rest against the outer surfaces thereof and hold the said screen from blowing inward. At a 105 distance from the bottom of the bars I suitable clamps J are provided, which are hinged to the bars I and made to close under the action of the coil-springs K. The upper and lower parts of these clamps J are flanged outwardly, as at J', and these parts are in alignment with the travel of the cams H on the 110 frame C. It will now be understood that as the sash is raised the upper cams H in ascent pass under the clamps J and lift them and hold them open until the screen is placed 115 under them. Then as the sash continues to rise the lower cams H allow the clamps J to gradually close and grip the lateral edges of the screen, so as to clamp it firmly against the side bars I intermediate of the window- 120 sill and the sash when fully raised. I have shown one of these clamps for each of the side bars I, as it is believed that one such clamp is sufficient; but it is evident that as many of such clamps as desired might be 125

130

used, and especially in those cases where the window-sash was raised to a very great distance. In ordinary windows the window-sash is not raised a distance which would require more than one such clamp on each side; but I do not restrict myself to the particular number of clamps that might be used.

It will be observed that I have made provision for all the possible adjustments that

- 10 might be necessary for readily and accurately adapting the screen to a window, for not only is the frame C attached so that it may be adjusted vertically at each end or either end to secure proper horizontality, but I have
- 15 provided the holding or clamping bar at the bottom of the screen with similar adjustability and of an automatic nature, so that the lateral edges of the screen are induced to remain taut under equal tensions. This is a
- 20 very important feature in the commercial application of my invention.

While I have shown the construction of my invention in the form in which I have found it most practical for commercial purposes, I do not restrict myself to the minor details, as it is evident to one skilled in the art that these may be materially modified in combining and assembling the various parts making up the complete structure.

- 30 Having now described my invention, what I claim as new, and desire to secure by Letters Patent, is—

1. In a window-screen, the combination of a frame adapted for attachment to the window-sash, a spring-roller secured thereto, a screen secured at one end to the spring-roller, and an end frame for the lower end of the screen having a bottom bar pivotally secured so as to adapt itself to the window-sill.

- 40 2. In a window-screen, the combination of a frame adapted for attachment to the window-sash, a spring-roller secured thereto, a screen secured at one end to the spring-roller, and an end frame for the lower end of the screen having an end bar secured to the screen and a bottom bar pivotally secured to the end bar so as to adapt itself to the window-sill.

3. In a window-screen, the combination of a frame adapted for attachment to the window-sash, a spring-roller secured thereto, a screen secured at one end to the spring-roller, an end frame for the lower end of the screen having a bottom bar having lugs F and pivotally secured so as to adapt itself to the window-sill, and side sockets I' adapted to be secured to the window-frame for receiving the lugs of the bottom bar.

- 4. In a window-screen, the combination of a frame adapted for attachment to the window-sash, a spring-roller secured thereto, a screen secured at one end to the spring-roller, an end frame for the lower end of the screen having a bottom bar pivotally secured so as to adapt itself to the window-sill, and side

bars for guiding the screen having their lower ends provided with sockets I' adapted to be secured to the window-frame for receiving the lugs of the bottom bar.

5. In a window-screen, the combination of the window-frame, a casing attachment to the window-sash and having cams on its ends, a spring-roller secured within the casing, a screen having one end secured to the spring-roller, a bottom bar for the screen for securing the lower end of the screen close to the window-sill, and L-shaped sheet-metal side bars attached to the parting-beads between the window-sashes and having flanged edges against which the lateral edges of the screen rest and provided with spring-actuated pivoted clamps carried wholly by the side bars and automatically operated by the cams on the casing for clamping the said lateral edges of the screen against the flanged edges of the said side bars intermediate of their ends, and also provided at their lower ends with means for locking the bottom bar of the screen adjacent to the window-sill.

6. In a window-screen, the combination of a frame adapted for attachment to the window-sash, a spring-roller secured thereto, a screen secured at one end to the spring-roller, an end frame having an adjustable bottom bar for connecting the lower end of the screen close to the window-sill, and L-shaped sheet-metal side bars having flanged edges against which the lateral edges of the screen rest and provided with pivoted spring-actuated clamps wholly supported by and arranged at or near their middle portions, and cams arranged beyond the end of the rollers adapted to be moved by the window-sash for operating upon said clamps beyond the screen to permit the insertion and removal of the screen in raising and lowering of the sash.

7. In a window-screen, the combination of a frame adapted for attachment to the window-sash, a spring-roller secured thereto, a screen secured at one end to the spring-roller, an end frame for the lower end of the screen having an adjustable bottom bar for connecting the lower end of the screen close to the window-sill, sheet-metal side bars against which the lateral edges of the screen rest provided with flanges for attachment to the parting-beads of the window-frame and having pivoted spring-actuated clamps at or near their middle portions, and cams on the frame carrying the spring-roller adapted to be moved by the window-sash for operating upon said clamps beyond the sides of the screen to permit the insertion and removal of the screen in raising and lowering of the sash.

8. In a window-screen, the combination of a frame adapted for attachment to the window-sash, a spring-roller secured thereto, a screen secured at one end to the spring-roller, an end frame for the lower end of the screen having a bottom bar pivotally secured so as

to adapt itself to the window-sill, and means connecting with the ends of the bottom bar for securing it to the sides of the window-frame close to the sill.

5 9. The side bar for a window-screen consisting of a bar L-shaped in cross-section for attachment to the parting-bead of the window-frame combined with a spring-actuated clamp pivoted directly to the said side bar intermediate of its ends.

10 10. The side bar for a window-screen consisting of a bar L-shaped in cross-section for attachment to the parting-bead of the window-frame and having a hook-shaped socket I' at the bottom extending transversely to the length of the bar combined with a spring-actuated clamp pivoted directly to the said side bar intermediate of its ends.

15 11. The bottom bar F² made U-shaped in cross-section combined with the end bar F' secured to the screen and extending into the bottom bar, and pivot f connecting the bars together so that the end bar may automatically adjust itself upon the bottom bar.

20 25 12. The screen-roller combined with the window-screen frame C formed of the two parts C' C² telescoping and forming the open

throat C⁵, and provided with the end plates C⁴ having the cams H entirely beyond the ends of the roller and lugs C³.

30

13. In a window-screen, the combination with the window-frame, a movable sash and spring-controlled screen connected with said sash and moved by it, of automatic clamping devices for clamping the side edges of the screen to the sides of the window-frame when the screen is drawn closed consisting of L-shaped sheet-metal side bars having flanged edges against which the screen is clamped, spring-actuated clamps hinged directly to the side bars and resting upon the flanged edges thereof so as to leave a space between them and the body of the side bars, and cams movable with the window-sash and traveling along the side bars and having pointed ends to engage the pivoted clamps beyond the side edges of the screen.

35

In testimony of which invention I hereunto set my hand this 12th day of September, 1905.

GEORGE HOLDEN.
